DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

1 Sheet Drawing, 8 Pages Specification

A combined system and method using liquefied natural gas for generating electricity and recovering potable water from saline water is provided. The liquefied natural gas cools air that is separated to produce oxygen that is combined with a portion of the vaporized natural gas for producing electricity preferably with a magnetohydrodynamic (MHD) generator. Additional refrigeration and kinetic energy gained from gas expansion are employed for vacuum freezing vapor compression desalination. Heat from the MHD generator may generate steam for producing additional electricity, and also heat water for vaporization desalination. Preferably a nuclear reactor is used for preheating oxygen and natural gas before reaction in the MHD generator.
